UNITED STATES PATENT OFFICE.

LEROY C. DOANE, OF MERIDEN, CONNECTICUT, ASSIGNOR TO THE MILLER COMPANY,
OF MERIDEN, CONNECTICUT, A CORPORATION OF CONNECTICUT.

SHADE HOLDER.

Application filed June 23, 1926. Serial No. 117,979.

The present invention relates to shadeholders and is more particularly directed toward a form of shadeholder suitable for supporting metal shades common in industrial lighting units and for providing a water proof 5 housing for the lamp socket.

An object of the present invention is to provide a shadeholder of the above character, the shadeholding parts of which may be made out 10 of cooperative sheet metal stampings which may be readily assembled and which are not likely to get out of order or become disassembled, and in which one may easily release or fasten a shade without the use of tools.

15 A further object of the invention is to provide an improved construction of the shadeholder and socket cover which may be readily supported about the socket.

20 Other and further objects of the invention will appear as the description proceeds.

The accompanying drawings show, for purposes of illustrating the invention, one of the many possible embodiments in which it may take form, it being understood that the 25 drawings are illustrative of the invention rather than limiting the same.

In these drawings:

Figure 1 is a vertical sectional view through the shadeholder, parts being in elevation;

30 Figure 2 is a sectional view on the line 2-2 of Figure 1 looking in the direction of the arrows;

Figure 3 is a section on the line 3-3 of Figure 1 looking in the direction of the arrows showing the parts in position for clamping a shade;

Figure 4 is a perspective view of the lower portion of the socket cover; and

40 Figure 5 is a perspective view of the movable ring used in actuating the shadeholding elements.

A two part conventional porcelain lamp socket is indicated at 10 and 11. A stud 12 is fastened to the upper end of the lamp socket 45 by screws indicated at 13. The stud 12 is internally threaded as indicated at 14 so that the socket may be carried from a suitable support. The lower part of the stud is outwardly flanged as indicated at 15, while the 50 intermediate part is, as here shown at 16, hexagonal, and the upper end is reduced and threaded as indicated at 17.

An inverted cup-shaped sheet metal stamping 18 surrounds the socket, acts as a socket 55 cover and is provided at the lower end with

shadeholding devices. The upper end 19 of the stamping 18 has a non-circular hole which fits about the hexagonal portion of the stud and the end of the stamping rests on the flange 15. A cap 20 is threaded onto the outside of 60 the stud and comes down onto it and engages with the upper end of the stamping to clamp it in place. The lower end 21 of the stamping 18 extends a short distance below the lower end of the lamp socket. It is provided with 65 a plurality of flexible tongues 22 which are pressed from the material of the stamping. The upper sides of these tongues are tapered as indicated at 22' and their ends 23 are bent 70 slightly outward.

A ring 24 has an inner wall 25 which fits about the lower end of the stamping 18. This inner wall has a number of apertures 26 through which the spring tongues 22 project. The outer wall 27 of the ring is spaced sufficiently from the inner wall to accommodate 75 the bead or lip 28 of a shade.

As clearly indicated in the drawing, the flexible tongues project outwardly through the apertures or slots 26. These slots are 80 short so that the opposite faces of the tongues are engageable with the opposite ends of the slots. When one turns a ring in a direction to clamp the shade, it causes the flexible 85 spring tongues to travel along the slots and effects a camming action upon the tongues to move them outwardly to the position of Figures 1 and 2 bringing the upper edges of the tongues against the end flange of the shade and directly supporting the shade from the 90 stamped socket cover. The thickness of these tongues is greater than the clearance between the inner wall 25 of the ring and the bead of the reflector. Owing to the oblique upper edge of the spring tongues, the reflector will be clamped tightly against the upper 95 part of the ring. This wedges the parts together, compensates for varying thicknesses of enamel, and does not make the supporting 100 of the shade dependent upon spring expansion. When one turns the ring in the opposite direction, the spring fingers will be compelled to retreat and release the shade.

In order to confine the ring and prevent its moving upwardly along the stamping 18, the stamping is preferably provided with a bead indicated at 29. To limit the angular movement of the ring and prevent its accidental removal, an inwardly directed prong 30 is carried on the inside wall 25 of the ring. 110

It projects into a slot 31 in the skirt 21 of the stamping 18. In assembling these parts, the stamping 18 is pressed sufficiently to permit the prong 30 to be pushed into position.

5 It will be noted, that the shadeholder which has just been described is made of a small number of simple parts which may be readily assembled and which are well suited for the purpose of covering the socket and supporting a shade from the stud which supports the socket so that no strain is placed on the socket itself. No amount of jarring or vibration will disengage the parts.

10 It is obvious that the invention may be embodied in many forms and constructions within the scope of the claims, and I wish it to be understood that the particular form shown is but one of the many forms. Various modifications and changes being possible, 15 I do not otherwise limit myself in any way with respect thereto.

What is claimed is:

1. In a shadeholder, in combination, a downwardly opening lamp socket, a stud carried at the upper end of the socket and having a non-circular portion and a threaded end, an inverted cup-shaped sheet metal stamping surrounding the socket and having a central aperture fitting the non-circular portion of the stud, a nut threaded onto the stud for clamping the stamping in place, and shade supporting devices carried at the lower end of the stamping, said shadeholding devices including a plurality of flexible tongues cut out of the material of the stamping and a movable ring having slots through which the tongues are passed, a partial rotation of the ring causing the tongues to spread to engage the shade.
2. In a shadeholder in combination, a downwardly opening lamp socket, a stamped sheet metal socket cover non-rotatably coupled to the socket, a plurality of flexible tongues cut out of the material of the stamping and a movable ring having slots through which the tongues are passed, the opposite faces of the tongues being engageable with the opposite ends of the slots to effect a camming action upon a partial rotation of the ring and cause the tongues to spread and engage the shade or to be withdrawn into the socket cover to release the shade, the stamping having a bead directly above the ring to prevent raising the ring whereby the shade is held down against the tongues.
3. In a shadeholder in combination, a downwardly opening lamp socket, a stamped

sheet metal socket cover non-rotatably coupled to the socket, a plurality of flexible tongues cut out of the material of the stamping and a movable ring having slots through which the tongues are passed, a partial rotation of the ring causing the tongues to spread to engage the shade, the upper edge of said tongues being oblique to effect a wedging action against the shade.

4. In a shadeholder in combination, a downwardly opening lamp socket, a stamped sheet metal socket cover non-rotatably coupled to the socket, a plurality of flexible tongues cut out of the material of the stamping and a movable ring having slots through which the tongues are passed, a partial rotation of the ring causing the tongues to spread to engage the shade, the stamping having a bead directly above the ring to prevent raising the ring, the upper edge of the tongues being oblique to effect a wedging action against the shade to press it toward the ring.

5. In combination, a shadeholder having a socket cover and a movable ring carried thereon, the socket cover having a plurality of outwardly directed spring tongues whose upper edges are oblique, the movable ring being of inverted U-shaped cross section and having apertures to receive the spring tongues, the ring being adapted to receive the lip or bead of a shade, the spring tongues being moved outwardly to engage the shade and secure it in place when the ring is moved in one direction, and being withdrawn to release the shade when moved in the other direction.

6. In combination a shade provided with a supporting bead having an inwardly directed flange, a fixedly carried stamped sheet metal socket cover and shade supporting device carried at the lower end of the socket cover, said shade supporting device including a plurality of flexible tongues cut out of the material of the stamping and a movable ring having slots through which the tongues are passed a partial rotation of the ring causing the tongues to spread to engage underneath the flange of the shade and support the shade directly from the socket cover, the socket cover having a bead against which the shade supporting device is held when supporting the shade whereby the shade is secured against upward movement.

Signed at Meriden, in the county of New Haven and State of Connecticut, this 11th day of June, 1926.

LEROY C. DOANE.
